WAVE SIGNALING SYSTEM

Application filed July 30, 1929, Serial No. 382,258, and in Great Britain August 10, 1928.

This invention relates to wave signaling systems such, for example, as high frequency electric systems for radiotelegraphy, radio-telephony, whether effected over an electrically conducting circuit or without tangible connection between signaling stations.

In such systems a plurality of channels of communication is provided by the use of a plurality of carrier waves of different carrier or basic frequencies and signals are effected by changing the amplitudes of or interrupting the carrier waves, or by slightly changing the basic frequency thereof.

It is generally supposed that for satisfactory communication the resonant apparatus employed should be broadly tuned, that is to say have a reasonably uniform response to the plurality of frequencies thus associated with a carrier frequency.

The invention comprises a system of wave signaling in which there is employed a resonant apparatus to deal with modulated wave forms, which has a high degree of selectivity of the order that is obtained by a piezo-electric device or a still higher selectivity.

Usually selectivity is improved by reducing the damping, but if the damping is reduced sufficiently to produce the required selectivity, there is involved a phenomenon which may be called persistence of oscillation, meaning the continuance of an oscillation in a resonant oscillatory apparatus after the excitation which set up the oscillation has ceased. It is obvious that the lower the damping of the resonant oscillatory apparatus the greater is this persistence, and that for high speed telegraphy, for example, this phenomenon militates against the ultimate receiver responding satisfactorily to the signal changes at the primary transmitter, since the oscillation produced by one signal may persist until the following signal arrives.

In wave signaling systems and particularly in high frequency electric signaling it is becoming increasingly important to maintain the efficiency of the receiver which involves a high degree of selectivity, but at the same time it is necessary to maintain a

high speed of signaling, and in the case of radio telephony, to maintain a faithful reproduction at the receiver of the signal applied to the transmitter.

An object of this invention is to provide a system in which these desirable qualities of selectivity and the accompanying efficiency are coupled with the facility for high speed telegraphic work and faithful telephonic reproduction.

The present invention comprises a system of wave signaling in which the damping of a resonant apparatus employed therein is less than that normally required for true reproduction of the initial signals and by the control of the energy in said resonant apparatus true reproduction is obtained therewith.

The damping above expressed as less than that normally required for true reproduction may be characteristic of an oscillatory apparatus having slight positive, zero or even negative resistance and the term "true reproduction" herein means the reproduction that is obtained when the energy in the oscillatory apparatus due to a signal dies away before the apparatus is re-energized by the next succeeding signal.

The invention also contemplates in a system of wave signaling (e. g. high frequency electric signaling), the use of resonant oscillatory apparatus having low damping and a selectivity of the high order that is obtained by means of resonant piezo-electric devices, in combination with means for quickly stopping out, either periodically or at predetermined times, oscillations therein which have been set up by excitation of the apparatus. By this means full use is made of the high selectivity of resonant oscillatory apparatus of low damping, but on the other hand, the persistence of oscillation, after the cessation of the excitation, is minimized.

One method of damping out the oscillations consists in intermittently introducing excitation of a reversed phase. Thus a source of high frequency energy may be applied, in two phases that are opposed, to the resonant oscillatory apparatus and one phase of the energy may be rendered active during

the period only when excitation of the resonant oscillatory apparatus is required and the other may be rendered active only when the damping out of an oscillation already set up in the resonant oscillatory apparatus is required. The periods of excitation in one phase and in the other phase of course need not be equal but will depend largely upon the characteristics of the oscillatory apparatus.

The stopping of the oscillation is effected periodically or rhythmically at a frequency lower than the carrier or basic frequency but higher than any of the frequencies used for signaling, such as the frequency of dots in Morse telegraphy or modulation frequencies in telephony or allied signaling. In applying this invention to carrier wave telephony either amplitude or frequency modulation may be employed.

The invention may be applied either to the transmitter or to the receiver of a high frequency electric signaling system or to both.

The accompanying drawings illustrate diagrammatically as examples several ways of carrying the invention into effect. In the drawings—

Figure 1 is a simple circuit arrangement, Figure 2 shows curves indicating the rise and fall of energy in typical oscillatory apparatus of different damping.

Figures 3, 4 and 5 are curves showing the manner of controlling the oscillatory apparatus according to the invention.

Figure 6 is a diagram of a receiver embodying the invention.

Figure 7 is a diagram of a transmitter.

Figure 8 is a diagram of a receiver embodying a resonator with negative resistance, and

Figure 9 is a diagram of a transmitter with two aerials.

Referring to Figure 1, a source of oscillator energy 10 (in this case electric energy) by means of which signaling is effected, is fed through coils 11 and 12 to a resonant oscillatory circuit 13, the arrangement of the coils 11 and 12 being such that the two resulting inputs to the oscillatory circuit 13 are opposed in phase.

The oscillatory circuit 13 includes a piezoelectric crystal 15 by means of which a high order of selectivity is obtained. By known means here shown simply by a key 14 for example (the valves and tuning apparatus usually employed having been omitted) energy is fed to the oscillatory circuit 13 by the coil 11 when excitation of the apparatus is required and the other coil 12 is energized during the intervening periods to damp out oscillations previously set up by the coil 11.

Alternatively, the reversal of phase of the excitation may be obtained by effecting a small change of frequency of the excitation

with the use of intermediate oscillatory apparatus sharply tuned to the mean of the excitation frequency.

Referring to Figure 2, there are shown applied on a time axis O—X against an axis O—Y representing amplitude in the resonant circuit, three curves 16, 17 and 18 representing the rise and fall of energy in three typical circuits of which that giving the curve 18 has the lowest damping. If for the purpose of this invention apparatus having a characteristic such as indicated by the curve 18 is chosen, the time which would be taken for excitation of this apparatus to die away with only its inherent damping, is much greater than the permissible time between successive signals, particularly in high speed signaling, and therefore a control of the energy in the oscillatory apparatus is necessary. If for instance by excitation of the apparatus the energy builds up to the point 38 on curve 18 the time O—39 for the excitation to die away due to the inherent damping is greater than is permissible but by control of the energy this time can be reduced to a satisfactory low value O—40.

This control may be effected by periodical reversing the phase of excitation; that is to say the energy in the apparatus is allowed to build up for say 50 cycles, and then is reduced in another period of say 50 cycles by the application of the excitation in opposite phase.

Thus, for continuous wave excitation there is obtained as shown in Figure 3, a period of "positive" excitation 19 obtained for example by means of the coil 11 in Figure 1, followed by a period of "negative" excitation 20 of opposite phase obtained by means of the coil 12. These periods alternate regularly and the resultant effect, as shown in Figure 4, is a succession of impulses 21 equal in length to the sum of a positive period 19 and a negative period 20. These impulses 21 are constituted by the rise and fall of energy in the oscillatory apparatus due respectively to each positive excitation 19 and the following negative excitation 20.

In the examples given above it has been assumed that the oscillatory apparatus has a slight positive resistance, but as previously stated, the apparatus may have zero or negative resistance. In the latter case if the negative impulses 20 are equal to the positive impulses 19, the damping produced by the controlling negative impulses is insufficient to bring the apparatus to a quiescent state at the end of each of the impulses 21 (Figure 4). In this case, therefore, the datum line upon which the apparatus functions will rise until it reaches a maximum steady level as shown in Figure 5. Thus the oscillatory apparatus can be allowed to reach this level upon which the variation due to the signals are imposed.

It will be understood that the periods of ex-

citation of the oscillatory apparatus by the coils 11 and 12 and thus the length of the impulses 19 and 20 need not be equal and will be suitably arranged according to the electrical characteristics of the oscillatory circuit such as the damping. For example when the oscillatory apparatus has slight positive resistance, then the impulses 20 need not be as long as the impulses 19 in order to bring the apparatus to a quiescent state at the end of each one of the signal impulses 21.

In applying the invention to a receiver, in the example illustrated in Figure 6 an antenna system 30 is connected to the control electrodes and cathodes of two thermionic valves 31 and 32 in parallel with one another. The anodes of the two thermionic valves may be respectively connected through coils 33 and 34 to opposite electrodes associated with a piezo-electric crystal 35 which is accurately tuned to the carrier or basic frequency used for signaling which may be for example 10^5 or 10^6 . The anodes are also connected respectively to opposite ends of an inductance 36 the centre point of which is connected to the positive pole of a D. C. supply 38 the negative of which is connected to the cathodes of the valves. The inductance 36 is coupled to a local source of alternating electric current 37 of a frequency preferably about 15,000 to 20,000 cycles per second in the case of telephony. In this method of carrying out the invention one of the valves is operative during one half cycle of the local alternating current and the other valve is operative during the other half cycle of the local alternating current. If desired, bias batteries may be connected in circuit with the anodes of the valves so as to render the periods of operativeness of the two valves unequal. It will be observed that the potential variations at the anodes of the two valves are in the same phase but that these are applied oppositely to the piezo-electric crystal. However, at any instant only one of the valves is in operation and during that time oscillations are set up in the piezo-electric crystal, which oscillations are reduced and stopped during the time that the second valve is in operation.

The piezo-electric crystal is a very highly selective resonant device and is only responsive to frequencies very close to that frequency to which it has been tuned. Consequently incoming signal frequencies different from that to which the piezo-electric crystal is tuned have little or no effect upon the crystal and the receiver is therefore rendered highly selective by the crystal but since the oscillations of the crystal are periodical-
ly stopped, the receiver is not subject to the defects caused by persistence of oscillation. One or both of the coils which are connected in series with the crystal may be coupled to a detector and receiver of conventional type as indicated diagrammatically in Fig. 6 of the

drawings. In Figure 6 the source of alternating current 37 for producing the difference in phase is applied to the anode circuits of the valves 31 and 32; it may alternatively be applied to the grid circuits. ⁷⁹

It will be understood that although in the examples described a piezo-electric crystal in conjunction with apparatus of low decrement is utilized, other equivalent means may be employed such for example as a thermionic ⁷⁵ valve system brought to a state of low damping or even negative resistance by the use of reaction.

In Figure 8 there is shown, by way of example, a receiver which is similar to that shown in Figure 6 with the exception that instead of a piezo-electric crystal 35, there is employed a resonator consisting of a retro-active thermionic valve system 41 having negative resistance. This thermionic valve system is energized by means of a coil 40 connected between the anodes of the receiving valve 31, 32 and has output terminals for the signals at 42. ⁸⁵

In applying the invention in one form of transmitter for telegraphy or telephony, there are employed (see Figure 7) two oscillatory circuits 50 and 51, which are tuned to the basic or carrier frequency and are shown as output circuits of thermionic valves ⁹⁰ 22 and 23 respectively so arranged that the circuits are excited in opposite phase. The input circuit of the valves indicated at 24 may be coupled in any suitable manner to the source of high frequency energy used for signaling. ⁹⁵ ¹⁰⁰

The two oscillatory circuits 50 and 51 are coupled by means of electromagnetic couplings 25 and 26 respectively to a circuit 27 energized by a controlling frequency of say ¹⁰⁵ 15,000 to 20,000 cycles per second. The arrangement is such that the two oscillatory circuits 50 and 51 are oppositely modulated, that is when the amplitude of one oscillatory circuit is at a maximum that of the other ¹¹⁰ oscillatory circuit is a minimum, and vice versa.

The resultant radiated energy therefore will change in phase rhythmically and by employing a controlling frequency of about ¹¹⁵ 15,000 to 20,000 cycles per second as above mentioned the rhythmic changes of phase are above audibility. The amplification to be obtained can be as large as is required.

The oscillatory circuits may be radiating ¹²⁰ systems or they may be coupled to one or more radiating systems. If a single radiating system is used as shown at 28, the oscillations caused by one half-cycle of the controlling frequency will be quickly damped ¹²⁵ out by the excitation by the other oscillatory circuit during the other half-cycle.

The oscillatory circuits 50 and 51 may be arranged to energize two separate radiating systems 43 and 44 as shown in Figure 9 which ¹³⁰

indicates a transmitting apparatus which is similar in other particulars to that shown in Figure 7. The aerials 43 and 44 are spaced apart and in this case oscillations set up by 5 one radiating system will be properly counteracted by a succeeding train of oscillations from the other radiating system in certain definite directions with respect to the positions of the radiating systems. These radiating systems might be beam aerials.

The invention is particularly applicable to systems employing frequency modulation as described in British specification No. 295,- 15 957 in which modulation is effected within the limits of frequency to which a piezo-electric crystal is responsive, that is to say, about 20 cycles.

In applying the present invention continuous wave energy is propagated from a transmitter and a speech or other form of signal 20 variations is caused to vary the frequency of the continuous wave energy within the narrow limits above indicated.

The frequency modulated energy is reversed in phase periodically according to one 25 feature of this invention either at the transmitter or at the receiver. With a receiver such as that indicated in Figure 6, there are obtained periods of positive and negative excursion as indicated in Figure 3 and signal impulses as indicated in Figure 4; for telephony the frequency of these latter impulses should be in excess of 10,000 cycles per second.

30 35 The modulation of the transmitted energy causes its frequency to be varied up and down say 10 cycles per second at the frequency of the signaling note, say 1000. The piezo-electric crystal of the receiver is adjusted with reference to the mean frequency of the oscillatory energy and since this frequency is 40 varied by the modulation, the piezo-electric crystal responds to a greater or lesser extent depending upon modulation. The response 45 of the piezo-electric crystal will thus follow the variations of the signal and consequently the amplitude of the impulses indicated in Figure 4 will rise and fall in magnitude in consequence of the modulation in this case at 50 a frequency of one value.

It will be appreciated that in order to receive the frequency modulated signals in which the range of modulation is a very narrow one such as that permissible with the 55 piezo-electric crystal it is necessary that the receiver should be properly responsive to such small variations in frequency. By the present invention there is provided a receiver having such a high degree of selectivity as to 60 be properly responsive to these variations in frequency, which receiver is also rendered operable in that the persistence of oscillation due to the low decrement of the receiver is properly and efficiently controlled.

65 It will be understood that where in the

system according to the invention as above described a piezo-electric crystal has been employed there may be alternatively used a valve system which is adjusted for example by means of reaction to have very little positive resistance and preferably zero or even negative resistance.

70 It is to be understood that the invention is not limited to the particular ways of using or applying the wave energy in reverse phase to the signaling energy in order to control the latter as above described, for example the required damping of the oscillations may be effected in accordance with the movement of a keying device as is done in the curbing of submarine signals.

75 80 Also the invention is applied to any wave transmission whether electric or acoustic and on line transmission at audio or higher frequencies.

85 I claim:

1. A receiver for wave signals comprising a resonant apparatus that is stable but has less damping than is usual for true reproduction so that oscillations tend to persist therein after the signal ceases, in combination with means for rhythmically altering the phase of the energy in the said resonant apparatus at a frequency lower than the carrier frequency of the received energy and higher than the highest modulation frequency of the received energy in order to subdue the persisting oscillations in the said resonant apparatus.

90 95 100 105 2. A receiver for wave signals comprising a resonant apparatus having a negative resistance characteristic such that free oscillations are set up therein and means for altering periodically the phase of the energy in the said resonant apparatus for the purpose of quenching the oscillations.

110 3. A receiver for wave signals comprising a resonant apparatus having a negative resistance characteristic such that free oscillations are set up therein and means for periodically reversing the phase of the energy in the said resonant apparatus for the purpose of quenching the oscillations.

115 120 125 4. A receiver for wave signals comprising a resonant apparatus having a negative resistance characteristic such that free oscillations are set up therein, means for applying the wave energy to the resonant apparatus in two phases that are opposed and means for alternatively rendering them active upon the resonant apparatus whereby the oscillations therein are periodically quenched.

5. A receiver for wave signals comprising a resonant apparatus having a negative resistance characteristic such that free oscillations are set up therein, two input circuits arranged to be excited by the received signals in two phases which are opposed and are fed to said resonant apparatus and means for rendering the energy in the two input

circuits alternately operative upon the resonant apparatus at a frequency that is greater than the signal frequency.

6. A receiver for wave signals comprising a resonant apparatus having a negative resistance characteristic such that free oscillations are set up therein, two input circuits arranged to be excited by the received signals in two phases which are opposed and are fed to said resonant apparatus and means for applying a subsidiary wave to said input circuits to produce opposite effects therein at any instant whereby said input circuits are rendered alternately operative upon the resonant apparatus to quench the oscillations therein.

7. A wave signaling system comprising a transmitter of wave signals, a receiver for said wave signals, said receiver having a resonant apparatus that has abnormally low damping so that oscillations tend to persist therein after the signal ceases with consequent signal distortion, and means in the system for rhythmically changing the phase of the wave energy that is effective in the resonant apparatus at a frequency differing from the frequency of the signals whereby the persisting oscillations are subdued and true reproduction of the signals is obtained.

8. A wave signaling system comprising a transmitter of wave signals, a receiver for said wave signals, said receiver having a resonant apparatus that has abnormally low damping so that oscillations tend to persist therein after the signal ceases with consequent signal distortion, and means at the receiver for rhythmically changing the phase of the energy in the resonant apparatus whereby the persisting oscillations are subdued and true reproduction of the signals is obtained.

9. A wave signaling system comprising a transmitter of wave signals, a receiver for said wave signals, said receiver having a resonant apparatus that has abnormally low damping so that oscillations tend to persist therein after the signal ceases with consequent signal distortion, and means at the transmitter for rhythmically changing the phase of the energy that is transmitted at a frequency differing from the frequency of the signals in order to produce a corresponding change of phase in the received energy in the resonant apparatus, whereby the persisting oscillations are subdued and true reproduction of the signals is obtained.

10. A wave signaling system comprising a transmitter of wave signals, a receiver for said wave signals, said receiver having a resonant apparatus that has abnormally low damping so that oscillations tend to persist therein after the signal ceases with consequent signal distortion, and means at the receiver for periodically reversing the phase of the energy in the resonant apparatus where-

by the persisting oscillations are subdued and true reproduction of the signals is obtained.

11. A wave signaling system comprising a transmitter for wave signals, a receiver for said wave signals, said receiver having a resonant apparatus that has abnormally low damping so that oscillations tend to persist therein after the signal ceases with consequent signal distortion, and means at the transmitter for periodically reversing the phase of the energy that is transmitted at a frequency differing from the frequency of the signals in order to produce a corresponding periodic phase reversal of the received energy in the said resonant apparatus, whereby the persisting oscillations are subdued and true reproduction of the signals is obtained.

12. In a receiver for wave signals, the combination with a resonant apparatus that is stable but has abnormally low damping so that signal oscillations tend to persist therein after the signal ceases with consequent signal distortion, of means for altering the phase of the energy in the said resonant apparatus in order to subdue the persisting oscillations therein and to obtain true reproduction of the signals.

13. A receiver for wave signals comprising a resonant apparatus that is stable but has abnormally low damping so that signal oscillations tend to persist therein after the signal ceases with consequent signal distortion, in combination with means for intermittently reversing the phase of the energy in the resonant apparatus in order to subdue the persisting oscillations therein and to obtain true reproduction of the signals.

14. A wave signaling system comprising a transmitter of wave signals, a receiver for said wave signals, said receiver having a resonant apparatus that has abnormally low damping so that oscillations tend to persist therein after the signal ceases with consequent signal distortion, and means in the system for rhythmically reversing the phase of the wave energy that is effective in the resonant apparatus at a frequency differing from the frequency of the signals whereby the persisting oscillations are subdued and true reproduction of the signals is obtained.

15. A wave signaling system comprising a transmitter of wave signals, a receiver for said wave signals, said receiver having a resonant apparatus that has abnormally low damping so that oscillations tend to persist therein after the signal ceases with consequent signal distortion, and means at the receiver for rhythmically reversing the phase of the energy in the resonant apparatus whereby the persisting oscillations are subdued and true reproduction of the signals is obtained.

In testimony whereof I affix my signature.
JAMES ROBINSON.
